UNITED STATES PATENT OFFICE.

STEPHEN SHANAHAN, OF CINCINNATI, OHIO, ASSIGNOR OF ONE-HALF TO CROWLEY-
PRAIRIE REALTY COMPANY, OF CHARLESTON, WEST VIRGINIA.

COVER BOX FOR METERS.

Application filed December 1, 1924. Serial No. 753,226.

To all whom it may concern:

Be it known that I, STEPHEN SHANAHAN, a citizen of the United States of America, and resident of Cincinnati, county of Hamilton, and State of Ohio, have invented certain new and useful Improvements in Cover Boxes for Meters, of which the following is a specification.

This invention relates to cover boxes for meters, and more specifically to a self-draining cover-box or enclosure for outdoor water-meters and the like.

The primary object of the invention is to provide a box-like cover for meters having a construction which insures ready and complete drainage of all water that may find access to the inside thereof, and which, therefore, is free from the troubles and dangers attendant upon the freezing of collected water in ordinary forms of such boxes.

In describing the invention in detail, reference is herein had to the accompanying drawings, in which—

25 Figure 1 is a top plan view of the invention, partly in sectional elevation; and—

Figure 2 is a vertical section on line 2—2, Fig. 1.

Referring to said drawings, 1 indicates a 30 casing of hollow pipe form designed as an enclosure for an outdoor meter (not shown), the same having a bell-like upper end providing an internal annular upwardly-facing ledge 2 and an encircling upright flange 3.

Permanently seated upon the ledge 2 is the horizontal base flange 4 of an inner covering for the casing-enclosed meter, and seated upon said base-flange, or upon a 40 gasket 5 which overlies said flange, is the lower end of a cylindrical main cover 6 which extends upward to a suitable height above the casing 1 and which is spaced from the casing flange 3 to provide for a 45 suitably calking 13. Said main cover has a closed upper end 6^a provided with an opening 7 through which access may be had to the interior of the cover, and disposed in closing relation to said opening is a removable 50 plate-like cap 8.

The inner covering hereinbefore referred to is designed to shield the casing-enclosed meter from water which finds access to the interior of the main cover 6 and to drain 55 such water to an outlet, as will hereinafter

be described. In the embodiment disclosed in the drawings, said inner covering comprises three separate members 9, 10 and 11, preferably formed of galvanized sheet metal, the member 9 being of upright hollow cylindrical neck-like form, having the flange 4 formed integral therewith. Said member 9 is spaced from the main cover 6 to form an intermediate channel 12 adapted for the reception of water as the latter drains from the other members constituting said inner covering. The member 10 constitutes a removable cover for the member 9, having a downturned flange 10^a adapted to seat in embracing relation to the neck portion of said member 9. Said member 10 has therein a central opening defined by an upright flange or neck 10^b, and disposed in embracing relation to said neck 10^b is the downturned flange 11^a 75 of the member 11, the latter constituting a removable cap for said opening and having a diameter sufficiently smaller than that of the opening 7 in the main cover 6 that it may be conveniently removed through the last mentioned opening, as for exposing to 80 view the dial of the meter. While it is apparent that the inner covering may be otherwise constructed and made of fewer parts, yet for purposes of convenience I prefer 85 to employ the construction described.

The casing 1 has therein a drain opening or passage 14 which opens upward through the ledge 2, apertures 15 and 16 provided in the base flange 4 and gasket 5, respectively, in register with said passage. While said passage may be otherwise arranged, it is preferred that it be disposed vertically, as shown, the wall of the casing 1 having a lug 17 formed thereon, or being otherwise thickened, to provide the required stock for the accommodation of such passage. Further, a tubular lining 18 of galvanized sheet metal is preferably disposed in said passage, and an outwardly extending drain spout 19 is 100 fitted into the casing at the lower end of said passage.

The passage 14 opens upward through the ledge 2 at a point outward with respect to the water-collection channel 12, due to the relatively narrow width of said ledge. Therefore, the main cover is provided with a recess 20 of suitable length and depth in that part of its lower edge adjacent to said passage, said recess being designed to per- 105 110

mit water collected in the channel 12 to flow unobstructedly to said passage. Due to the fact that the enclosure is at all times kept free from the collection of water, freezing 5 of the meter is effectively eliminated.

What is claimed is—

1. An enclosure for meters, comprising a casing having at its upper end an upright flange and having an internal annular ledge, 10 located inwardly with respect to said flange, an inner covering having a base flange seated on said ledge, an outer cover seated upon said base flange and spaced from said inner covering to form an intermediate annular channel, and a drain passage leading outward 15 from said channel through the casing wall.
2. An enclosure for meters, comprising a casing having at its upper end an upright flange and having an internal annular ledge, 20 located inwardly with respect to said flange, an inner covering having a base flange seated on said ledge, an outer cover seated upon said base flange and spaced from said inner covering to form an intermediate annular channel, and a drain passage leading outward 25 from said channel through the casing wall, said passage opening upward through said ledge.
3. An enclosure for meters, comprising a casing having at its upper end an upright flange and having an internal annular ledge, 30 located inwardly with respect to said flange,

an inner covering having a base flange seated on said ledge, an outer cover seated 35 upon said base flange, said cover being spaced from said flange to provide for the reception of calking material and being spaced from said inner covering to form a water-collection channel, said inner covering including a removable cap and said outer cover having therein an opening through which said cap may be inserted and removed, and a removable closure for said opening, the wall of said casing having a 40 drain passage leading outward therethrough from said channel.

4. An enclosure for meters, comprising a casing having at its upper end an upright flange and having an internal annular ledge, 45 located inwardly with respect to said flange, an inner covering having a base flange seated on said ledge, an outer cover seated upon said base flange and spaced from said inner covering to form an intermediate annular 50 channel, said cover having a recess in its seating edge, the wall of said casing having therein an outwardly extending drain passage which opens at its upper end through said ledge, communication between said passage and said channel being had through 55 said recess in the cover.

In testimony whereof, I affix my signature.

STEPHEN SHANAHAN.
